UNITED STATES PATENT OFFICE.

ELWOOD F. BOSTWICK, OF NEW YORK, N. Y.

DESIGN FOR A CONDIMENT-HOLDER.

49,049.

Specification for Design.

Patented May 16, 1916.

Application filed February 7, 1916. Serial No. 76,856. Term of patent 3½ years.

To all whom it may concern:

Be it known that I, Elwood F. Bostwick, a citizen of the United States, residing at New York, in the county and State of New York, have invented a new, original, and ornamental Design for Condiment-Holders, of which the following is a specification, reference being had to the accompanying drawing, forming a part thereof.

The figure is a perspective view of a condiment holder showing my new design.

I claim:

The ornamental design for a condiment holder as shown.

ELWOOD F. BOSTWICK.
